FIG. 1

FIG. 4

FIG. 1 is a plan view of a swab for cosmetic application, showing by dotted lines a removable and replaceable applicator member formed as a sleeve on the end of the design.

FIG. 2 is a view similar to FIG. 1 showing the design turned 90° from its position in FIG. 1.

FIG. 3 is an end elevation of the applicator with the swab member removed; and

FIG. 4 is a perspective view of the swab carrier shown for clarity of illustration.

The broken lines are shown for illustrative purposes only.

We claim:

The ornamental design for a swab for cosmetic application, as shown and described.
